UNITED STATES PATENT OFFICE.

CARL OTTO SEGESMUND ANDERSON, OF LONG ISLAND, NEW YORK.

MUSIC-SHEET FOR PLAYING INSTRUMENTS.

1,321,076.

Specification of Letters Patent. Patented Nov. 11, 1919.

Application filed June 4, 1917. Serial No. 172,830.

To all whom it may concern:

Be it known that I, CARL OTTO SEGESMUND ANDERSON, a citizen of the United States, residing at Long Island, in the county of Queens and State of New York, have invented new and useful Improvements in Music-Sheets for Playing Instruments, of which the following is a specification.

10 This invention has to do with perforated traveling music sheets adapted to be employed on pianolas, player pianos and similar apparatus having pneumatic trackers, and the main object of the invention is to 15 provide the perforated music sheet with the written musical composition in order to present or visualize the same in proper succession to the operator or bystander in agreement with the translation of the note perforations into the melody, so that the written composition may be read and sung from 20 the music sheet itself as the player piano or apparatus employing it is operated.

Another object of the invention is to 25 place the musical composition on the face of the music sheet in such manner as to permit the musical characters and the words to be made in such size that they can be readily followed and read at a distance by the average person, and also that two or more staves 30 including the musical characters and words may be placed on the music sheet so that the various divisions of the melody may be presented and visualized to enable the singing 35 of the composition in its various parts or for the use of performers on string or wind instruments.

With these and other objects in view, the invention consists in securing to or printing 40 on the perforated traveling music sheet, sections or divisions of the musical composition in spaced-apart position in proper consecutive order from the beginning of the composition to the end thereof, as will be 45 more fully described in the following specification.

The character of the invention may be 50 explained and illustrated more conveniently by reference to the embodiment illustrated in the accompanying drawing, which represents a fragment of a perforated music sheet of conventional type having sections of the musical composition including the words printed on the face thereof in the preferred 55 inclined position in parallelism, there being

also illustrated in this connection a portion of a pneumatic tracker.

In the use of pianolas, player pianos and like apparatus, the operator or bystanders often desire to follow the conventionally written notes of the tune and the words to sing the same as the composition is being translated into melody by the apparatus, when the usual printed sheet music is not available at the time, or cannot be found on the moment without the inconvenience of a search. Thus, it frequently happens that there is a genuine need to have the written musical composition including the words available instantly as the melody is being reproduced by the apparatus. It is with a view of meeting this need that the written composition including the words has been combined with the perforated traveling music sheet in the manner herein disclosed.

In the accompanying drawing, the numeral 1 denotes a fragmentary portion of a sheet of conventional type, provided with the usual note perforations as 2, adapted to register with the apertures as 3 of 80 the tracker board 4 for the reproduction of the melody in the usual way.

Upon the face of this sheet is printed, written, or otherwise secured by suitable sections or divisions in parallel spaced-apart positions, the staves including the notes, characters and words of the composition, the staves being either single as 5, representing but one part or division of the melody or comprising two or more staves as 6 representing the treble and bass clef parts or keys of the melody. These staves may comprise the musical subject-matter for singing purposes only, or they may comprise the necessary musical subject-matter 90 for the use of performers on violins, guitars, banjos, cornets, trombones, or any other string or wind instrument.

In the illustration presented in the accompanying drawing, the fragmental perforated note sheet 1 is shown with a melody in one stave as 5 including the notes, words, and expression indications as 7 printed on the bottom portion, while a continuation of the melody in proper sequence but here 105 shown written in three staves as 6 with the accompanying notes and words is printed on the upper portion. It will be understood in this connection that the single stave and the triple staves are shown here on the same 110

fragmental note sheet only for the purpose of illustrating how the different staves as desired may be printed on the note sheet, but that in manufacture, as a rule, the musical notation will be printed on the same note sheet in the same number of staves in proper succession just as it appears in all substantial respects on the conventional printed music sheet.

10 In the accompanying drawing, it will be observed that the staves are printed on the music sheet in inclined position transverse the music sheet and that the accompanying musical characters and words are 15 read from left to right in the conventional manner.

The desired stave divisions and musical characters from the beginning of the musical composition to the end thereof, with or without 20 cut the accompanying words may thus be printed in proper consecutive order in uniformly spaced-apart and inclined positions on the perforated music sheet from beginning to the end thereof, the notes and words 25 of the musical composition appearing approximately in the same horizontal plane for the corresponding note perforations of the music sheet. Thus, in the accompanying drawing, in the stave represented by 30 the numeral 5, the first note thereof, together with the first word You is intended to lay approximately in the same horizontal plane as the corresponding note perforations, here represented for convenience of illustration 35 as 3. Similarly the succeeding note and the word Ask come approximately in the horizontal plane traversed by the corresponding note perforations therefor.

In a similar manner throughout the entire 40 music sheet, the note or notes and the accompanying word or words are intended to come approximately in the horizontal plane traversed by the corresponding note perforations of the music sheet, the stave sections, accompanying characters and words 45 always beginning on the left-hand side of the sheet and always ending on the right-hand side, in the proper consecutive order of the musical composition, the ends of the 50 two adjacent sections of staves over-lapping slightly if necessary or as may be necessary in the same horizontal plane, in order to bring the notes and words thereof in the desired alignment with the corresponding note 55 perforations of the music sheet.

By thus arranging the staves inclinedly or obliquely of the music sheet, I obtain distinct advantages. It enables me to print the musical characters and the words in such size 60 that they may be read at a distance by the

average person. Again, when the operator or bystander desires to read the notes or to sing, it is only necessary for him to follow the horizontal plane of the tracker board as 65 4, since the music and words printed on the traveling music sheet as 1 are carried over this plane uniformly from the left to the right, the beginning of each stave section including the words being carried over the left hand side end of the horizontal plane of 70 the tracker board, while the end of each stave including the words is carried across this plane at the right-hand end of the tracker board.

Thus, in this manner I arrange to print 75 or otherwise secure the musical composition upon the traveling note sheets so that, as the melody is reproduced by the note perforations passing over the tracker board, the corresponding written notes and words are 80 visualized simultaneously in front of the tracker board, permitting the written music and words to be read and the melody to be sung, if desired, with convenience during the playing of the instrument.

Having thus described my invention, what I claim is:—

As a new article of manufacture, the herein-described traveling music sheet having within the same area the note perforations for the tracker board of a self playing instrument and the written musical composition of which the note apertures represent the mechanical translation, said note apertures being provided in parallel lines 85 lengthwise of the sheet and being of varying lengths, presenting thereby between the perforations parallel imperforate lines and imperforate interstices, said musical composition being subdivided into sections which 90 are printed obliquely upon said intervening imperforate lines and interstices and across the note apertures, said sections consisting 95 of straight stretches in spaced parallel sequence as written in a music book but presented obliquely of the sheet and within the compass of the perforated area, each of said sections being made up of measures, and the musical characters included in each measure coming opposite or approximately opposite the note aperture or apertures corresponding thereto, whereby in synchronism to visualize the measures including their component musical characters with the corresponding note apertures as the latter cross 105 the tracker board.

In testimony whereof, I have signed my name to this specification.

CARL OTTO SEGESMUND ANDERSON.
